UNITED STATES PATENT OFFICE

FRED. L. RICHARDSON AND LAURIE S. MACDONALD, OF BROCKTON, MASSACHUSETTS,
ASSIGNORS TO THOMPSON BROS. SHOE CO., OF BROCKTON, MASSACHUSETTS, A COR-
PORATION OF MASSACHUSETTS

CORRECTIVE SHOE

Application filed June 27, 1929. Serial No. 374,012.

This invention relates to shoes of the corrective type and more particularly that type of shoe in which the inner sole, at its shank portion beneath the arch of the foot, is provided with lateral extensions upwardly turned to afford supporting means for the main longitudinal arch of the foot, such a shoe, for example, as is disclosed in the United States patent to George R. Davis, No. 10,1058,561.

In order to afford proper support on opposite sides of the arch through these extensions it is desirable that the inner sole of the shoe bottom shall be fairly heavy, but in the manufacture of such shoes with the proper weight of inner sole there has been encountered difficulty in moulding the lateral arch supporting extensions to give them a sharp enough upward curvature from the body of the insole 20 to snugly embrace or hug the arch portion of the foot which they are intended to engage. The problem is further complicated by the fact that the forward portion of the arch subtending or shank portion of the insole is 25 inclined downwardly toward the forepart, since the shank portion is, and should be, on a somewhat higher level than the forepart of the shoe bottom. Such downward bending tends to force the forward end portion of 30 the main extension outward away from the foot. It is also desirable that the inner sole be not materially weakened along the lines where the relatively flat inner sole body joins the upturned arch supporting extension.

The present invention affords a solution of these difficulties by providing an inner sole construction which permits the sharp upward bending of the arch supporting extensions along clearly defined lines of juncture without sacrificing the strength of the inner sole 40 and consists, generally speaking, in a construction of inner sole of sole leather having a lateral extension on either, or preferably on both, sides of the shank portion of the body 45 of the inner sole, which extension is integral- 50 ly united throughout the flesh or fibrous layer of the sole leather and is severed throughout the grain layer of the inner sole on a line substantially following the usual contour of the shank portion of an insole, thereby elimi-

nating resistance of the stiff grain layer to the proper bending upward of the extension while retaining practically the full strength of the leather at the point of juncture by the absence of any severing cut through the 55 fibrous layer of the inner sole. Moreover, this severance of the grain layer, while leaving the more flexible but tougher fibrous layer intact, permits that portion of the inner sole where the shank portion merges with the fore- 60 part to bend downward without tending to force outward the extension member on the inner or ball side of the shoe.

This and other features of the invention will be particularly described in the following specification and will be defined in the claims hereto annexed.

In the accompanying drawings we have illustrated the preferred construction embodying the principles of this invention, in 70 which

Fig. 1 is a top plan view of an insole blank showing the severing lines or channels partly separating or dividing the lateral arch supporting extensions from the main body portion of the inner sole. 75

Fig. 2 is a cross sectional elevation on dotted line plane 2—2 of Fig. 1.

Fig. 3 is a plan view of the inner sole blank with the lateral extensions upwardly moulded 80 before attachment to the last for lasting the upper.

Fig. 4 is a side elevation of the moulded inner sole shown in Fig. 3.

Figs. 5 and 6 are cross sectional views respectively on the dotted line planes 5—5 and 6—6 of Fig. 3. 85

Fig. 7 is a cross sectional elevation through the middle portion of the shank showing the shoe upper lining and the reenforcing bands 90 united with the shoe bottom.

In the practice of the invention the inner sole of sole leather is cut out in the usual form, except that the shank portion is provided with integral outwardly projecting 95 lateral extensions 2 and 3 which are to form the arch supporting members or segments in the completed shoe.

With a suitable cutting tool channels 4 and 5 are gouged out of the top or grain side of 100

the inner sole so as to sever the stiff heavy layer of the main body portion 1 of the inner sole from the grain layer of each lateral extension or segment. Preferably this severance line cutting through the grain layer follows the usual or normal contour of an inner sole for an ordinary shoe which is markedly concave on the inner or ball side of the shank and somewhat less concave on the outer side 10 of the shank portion of the shoe. The cutting tool should actually cut away the grain along these lines so as to leave narrow channels extending down practically to the fibrous or flesh layer of the sole leather which is the 15 tough or tenacious portion of the sole leather, while the grain layer of somewhat horn-like texture is the stiffening layer of the sole leather but adds little to its tensile strength.

It will therefore be seen that the integral 20 connection between the flesh layers of the body portion and of the arch supporting extension is not weakened by this channelling process while the stiffness along the line of upward bend is largely eliminated. Furthermore, a very definite line of sharp bending 25 can be established by reason of the removal or cutting away of the stiff grain layer on these lines 4 and 5. Furthermore, by reason of the elimination of this stiffening at 30 the forward end of the main or ball side extension at 4^a the tendency of the downward bending of the forepart at this point to force outward the adjacent portion of the main extension 2 is substantially eliminated.

When the blank has thus been channelled 35 it may be placed in the moulding machine or press and it will be found that both extensions can be given an abrupt upward curvature along the normal contour lines of the 40 shank portion of an inner sole, thereby enabling the lateral arch supporting extensions to closely hug the upward curvature of the foot at these points, which is an effect greatly desired but not heretofore practically accomplished.

After the inner sole thus channelled on its 45 top or grain side has been thus moulded, it is ready to be attached to the last on which the complete shoe is to be built. The inner sole is channelled on the bottom or flesh side to form the welt attaching lips 6 to which the interior lining 7, the upper 9 and the intermediate straps or reenforcing bands 8, shown in the aforesaid Davis patent, are united by stitching, following which the outer sole 10 is attached by the usual stitching operation.

It will therefore be seen that the weight 50 and strength of the inner sole is not sacrificed, while at the same time the arch supporting extensions are turned upward on clearly defined and appropriate lines of juncture with the flat portion of the inner sole body to closely hug the corresponding portions of an inserted foot.

55 The outer edge of each extension should be

thinned or skived down to avoid forming a ridge in the shoe upper. In this case the flesh or fibrous layer of the sole leather is cut away leaving the grain side intact except at the tip so as to preserve the stiffness in the 70 edge portion of the extension.

What we claim is:

1. An inner sole for a corrective shoe embracing an integral sole leather body of usual contour comprising grain and fibrous layers 75 and having lateral extensions projecting from opposite sides of the shank portion, the fibrous layer of the extensions being integral and continuous with the fibrous layer of the inner sole body while the grain layer of the extensions is cut through to separate it from the body along the shank line, thereby permitting the extensions to be turned sharply upward to snugly embrace the arch of a foot without materially weakening the inner sole 80 along the line of the cuts.

2. A moulded inner sole for a corrective shoe embracing an integral inner sole leather body of usual contour, comprising a top grain layer and a bottom fibrous layer and having a lateral extension projecting from the shank portion of the inner sole and moulded to turn abruptly upward along the concave line of inner sole body portion, the grain layer being channelled along said line leaving the fibrous 95 layer intact, the forward end of said channel extending through the grain layer to the edge of the ball portion to allow the insole forepart to bend downward while allowing the adjacent end of the extension member to turn 100 sharply upward.

3. An inner sole for a corrective shoe embracing an integral sole leather blank comprising an upper grain layer and a lower fibrous layer, having projecting out from the 105 normal concave contour of the shank a lateral extension whose fibrous layer is continuous and integral with the fibrous layer of the body portion but having its grain layer separated from the grain layer of the body portion by removal of a narrow strip of the grain layer along the concave line of the inside edge of the shank, said extension being turned abruptly upward along said concave line to afford support for the ball side of 115 the foot arch.

4. An inner sole for a corrective shoe embracing an integral sole leather blank comprising an upper grain layer and a lower fibrous layer, having projecting out from the 120 normal concave contour of the shank a lateral extension whose fibrous layer is continuous and integral with the fibrous layer of the body portion but having its grain layer separated from the grain layer of the body portion by removal of a narrow strip of the grain layer along the concave line of the inside edge of the shank, said extension being turned abruptly upward along said concave line to afford support for the ball side of 125 130

the foot arch, the fibrous layer of the extension being skived off along its outer edge portion to leave a thin edge portion wholly of grain layer.

In witness whereof, we have subscribed the
5 above specification.

FRED. L. RICHARDSON.
LAURIE S. MACDONALD.
